US00D960851S

(12) **United States Design Patent** (10) **Patent No.:** **US D960,851 S**
(45) **Date of Patent:** **** Aug. 16, 2022**

(54) **MOBILE PHONE**

(71) Applicant: **THE LIGHT PHONE INC.**, Brooklyn, NY (US)

(72) Inventors: **Kaiwei Tang**, Brooklyn, NY (US); **Joseph Hollier**, Brooklyn, NY (US)

(73) Assignee: **THE LIGHT PHONE INC.**, Brooklyn, NY (US)

(**) Term: **15 Years**

(21) Appl. No.: **29/722,858**

(22) Filed: **Feb. 3, 2020**

(51) LOC (13) Cl. **14-03**

(52) U.S. Cl.

CLAIM

The ornamental design for a mobile phone, as shown and described.

DESCRIPTION

FIG. 1 is a top perspective view of a mobile phone showing our new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof; and,

FIG. 8 is a left side elevational view thereof.

The broken lines in the drawings illustrate portions of the mobile phone that form no part of the claimed design.

1 Claim, 2 Drawing Sheets
